MACHINE FOR TUFTING MATTRESSES

Martin H. Lang, Minneapolis, Minn.

Application October 15, 1934, Serial No. 748,366

14 Claims. (Cl. 112—3)

This invention relates to a mattress tufting machine of the type constructed and arranged to insert successive rows of spaced tufts in a mattress.

5 It is an object of this invention to provide a simple, compact and efficient machine which will compress the mattress along a narrow zone so that the mattress will be compressed equally from top and bottom.

10 It is another object of the invention to provide a machine having means for compressing a mattress and inserting tufts through the compressed portion at spaced intervals, together with means for moving the mattress toward the compressing and tufting means at intervals to form successive rows of tufts therein.

15 It is another object of the invention to provide a mattress tufting machine having means for supporting a mattress and bars disposed above and below said mattress extending thereacross and movable toward each other to compress said mattress, said bars being convex in cross section at their adjacent portions.

20 It is still another object of the invention to provide a mattress tufting machine having a mattress-supporting table and bars extending transversely thereof adapted to be moved together to compress said mattress along a narrow zone, said bars being constructed and arranged to move equal distances toward each other after engaging said mattress on said table so that said mattress is equally compressed from its top and bottom.

25 It is more specifically an object of the invention to provide a mattress tufting machine having means for compressing a mattress along a narrow zone extending transversely thereof, a bar extending parallel to said means and a carriage supported entirely by said bar and having rollers journaled thereon engaging said bar.

30 These and other objects and advantages of the invention will be fully set forth in the following description made in connection with the accompanying drawings, in which like reference characters refer to similar parts throughout the several views and in which:—

Fig. 1 is a view in front elevation of said machine;

Fig. 2 is a partial view on an enlarged scale 35 of a portion shown in Fig. 1, said view being partly in plan and partly in horizontal cross section;

Fig. 3 is a top plan view of said machine;

Fig. 4 is a view in side elevation of said machine as seen from the left of Fig. 1;

Fig. 5 is a view in vertical section taken substantially on line 5—5 of Fig. 1 as indicated by the arrows;

Fig. 6 is a horizontal section taken on line 6—6 of Fig. 4 as indicated by the arrows;

Fig. 7 is an enlarged vertical section on line 7—7 of Fig. 1; and

Fig. 8 is a view in elevation as seen from the right of Fig. 7.

Referring to the drawings, a mattress tufting machine is shown comprising a frame having the end members 10 illustrated as in the form of castings having the forward and rearward foot portions 10a and 10b and being generally of triangular form. Said end members are connected and rigidly tied together by a plurality of bars 11 which extend therebetween and are provided with nuts 12 engaging said end members. A table 13 is provided comprising spaced members or boards 13a extending forwardly and rearwardly of said machine, said boards at their forward ends being supported in an angle member 14 secured to the end members 10. Said boards adjacent their rear ends are also secured to an angle bar 15 which is secured at its ends 25 by bolts 17 to the upper apertured ends of a pair of links 18, through the other ends of which pass one of the lower rods 11. Boards 13a are secured to bars 14 and 15 by bolts 16 having heads countersunk into said boards. The end boards 13a have metal plates 19 set into their top edges so that their top surfaces are flush with the top surfaces of said boards, said boards being rabbeted or cut away below the outer edges of said plates as shown at 13b in Fig. 6. 30

Said end members 10 each have an apertured lug 10c at their upper forward ends. Each of said end members has a recess 10d below said lug extending to the horizontal surface 10e. Guide rods 20 shown as of cylindrical form are 40 secured in the lugs 10c. A bar 21 extends between guide rods 20 and has apertured lugs 21a at its ends slidable on said guide rods below lug 10c. Bar 21 is shaped as shown in Figs. 1 and 5, the same having its central portion somewhat 45 above the end lugs 21a, said central portion being of convex shape on its upper side and being provided with a central aperture 21b and a plurality of elongated apertures or slots 21c at each side of aperture 21b. Said bar has a plurality of spaced trough-shaped lugs 21d projecting at its forward side and a table 22 has a downturned edge 22a seated in said lugs. Said table 22 is in the form of a plate preferably made of metal and the same has secured to its 50

55

under side small brackets 23 having hook-shaped portions which extend under the lugs 21d as shown in Fig. 5. The structure of members 22 and 23 just described, together with the lugs 21d, form a hinge or hinges so that table 22 can swing about the axis of lugs 21d. Table 22 has a downwardly extending front side 22b and said table is connected at its ends by pins 22c to the upper apertured ends of links 24 which 10 have apertured lower ends through which passes a shaft 25 journaled in lugs 10f on end frames or members 10. Another bar 26 is provided extending between guide rods 20 and having apertured end lugs 26a slidable on the guide rods 15 20. Bar 26 is shaped as shown in Figs. 1 and 5 and has its central portion disposed below the lugs 26a, said central portion having a lower convex surface and being provided with apertures 26b similar to and aligned with the apertures 21b and 21c of bar 21. Bar 26 has bosses 26c at its ends into which extend pins 27. Pins 27 extend through the upper apertured ends of links 28, said links being held thereon by the washers 29 and cotter pins 30. Links 28 extend 25 downwardly and have their other ends pivoted by pivots 31 to levers 32 secured to shaft 25. As shown in Fig. 4 links 28 are formed on an obtuse angle longitudinally and have their lower ends curved rearwardly to engage pivot 30 members 31. Bar 21 has bosses 21e in which are secured the pins 33 which pass through the upper apertured ends of links 34, said links being secured on said pins by the washers 35 and the cotter pins 36. Links 34 extend downwardly 35 and are secured by pivot pins 37 to angle levers 32. It will be noted that in the position of lever 32 shown in Fig. 4, pivot 37 is above shaft 25 and is closer to shaft 25 than the pivot 31, which latter is below shaft 25. Arms 38 have 40 hubs through which shaft 25 passes, which hubs are secured to said shaft by the set screws 39. Said arms 38 are rectangular in shape and are disposed in a slot 40a extending longitudinally through the side of a counterweight 40, which 45 counterweight is adjustable along arm 38 and held in fixed position thereon by set screw 40b. A collar 41 is secured to shaft 25 by set screw 41a at the inner side of each link 24 to hold said links in position. Lever 32 has arms extending 50 therefrom substantially at right angles, which arms are provided at their ends with handles 32a.

The bar 26 has a plurality of bosses 26d at its upper rear side having flat surfaces to which 55 are secured by the bolts 42, a flat bar or cross rail 43 which extends above and below said bosses. Bar 43 is beveled at its upper and lower edges so that it is of V-shape at said edges in cross section. Bar 43 has moving in engagement with its upper side a pair of rollers 44, while a roller 45 disposed centrally between rollers 44 engages its lower side. Rollers 44 and 45 have V-shaped grooves in their peripheries fitting said bar so that there is no lost motion between said rollers and bar. Rollers 44 and 45 are journaled on studs 46 secured to a bracket or carriage 47, which studs are headed and also secure said rollers to said carriage. While various structures of roller and bearing might be 60 used, in the embodiment of the invention illustrated said studs 46 have a body portion 46c which fits in the inner shell 44a of a ball bearing casing. Shell 44a is provided with two spaced ball bearing tracks or races of the two-point type 65 in which travel the balls 44c. Said balls also

travel in similar races formed in the outer shell 44b of the ball bearing casing, which races are aligned with said races in said inner shell 44a. The outer shell 44b fits tightly in a recess or bore in the roller 44 and said roller is also bored at one side so that the head of stud 46 is partially received therein. The ball bearing casing is held in roller 44 by a ring 44d which is threaded into the outer end of the bore which receives shell 44b. Said ring may be rotated to be screwed into place or removed by a spanner wrench fitting in holes 44f therein. Ring 44d is bored to receive a smaller ring or washer 44e which is in turn bored to fit on portion 46c of stud 46. Stud 46 has a reduced terminal portion 46b which is eccentric to portion 46c. Portion 46b extends through the bracket 47 and receives a nut 46a which engages the outer side of bearing 47. Stud 46 has its head provided with a slot 46d extending diametrically there-across adapted to receive a screwdriver for rotating said stud. Ring 44e projects slightly beyond the shoulder formed by portion 46b on stud 46 and when nut 46a is tightened ring 44e is clamped between bracket 47 and the inner shell 44a of the ball bearing casing by head 46 of the stud. Said inner casing of the stud is thus held in stationary position. It will be seen that by rotating stud 46, which can be rotated in bearing 47 about the axis of portion 46b, that roller 44 can be brought nearer to or farther away from the supporting rail 43. The rollers 44 and 45 can thus be moved toward or from rail 43 and a proper fit of the rollers on the rail maintained so that there will be no play or loose movement between said rollers and rail. Carriage 47 has forwardly projecting lugs 47a and 47b which are bored to have fitting and slidable therein a spindle 48. Spindle 48 is bored at its lower end to have secured therein a needle 49 shown as held in place by a screw 50. Spindle 48 passes through and is secured in a block 51 bored to receive the same, which block has bosses at its sides which fit between the arms 52a of a hand lever 52. Studs 53 extend through arms 52a into the block 51 so that it is pivotally connected to the lever 52. The arms 52a extend at either side of bracket 47 and unite in the rear of said bracket with a rearwardly projecting apertured portion 52b of said lever 52. Portion 52b has links 54 at either side thereof pivoted thereto on a pivot 55 and secured by the cotter pins 56. Links 54 are pivoted at their lower ends at either side of bracket 47 to a pivot 58 passing through said bracket and said links are also secured at their lower ends by the cotter pins 59. The arms 52a have headed pins 60 projecting from their inner sides, to which are secured the lower ends of a pair of tensile coiled springs 61, which springs are secured at their upper ends to pins 62 projecting from either side of the upper end of bracket 47. Small brackets 63 are secured to the front of bar 43 and are apertured to receive pins 64 as shown in Fig. 2. A bracket 65 having a square socket 66 therein is disposed at the inner side of each bracket 63, the same having an aperture in its end through which passes pin 64. A compression coil spring 66 surrounds pin 64 within one of brackets 65, bearing at one end against the end of bracket 65 and at its other end against the end of a square bar 67 having its ends fitted into the sockets in brackets 65 and extending between said brackets. Bar 67 has spaced marks 68a thereon arranged to indicate different po-

sitions for the spindle 48 and thus for carriage 47 to locate the tufts inserted by needle 49. The marks on the different sides of bar 67 are differently spaced so that said bar may be turned 5 and sides with differently spaced marks be disposed forwardly.

A plate or board 70 extends across the table 13 at right angles to the boards 13a, the same being disposed in a vertical plane and secured at its 10 outer ends to brackets 71 by the bolts 72. Plates 73 are also secured to said board 70 and brackets 71, the same being shown as disposed between the front side of brackets 71 and the rear side of board 70 and as extending forwardly along the 15 ends of board 70 and some distance forwardly of said board and having their outer forward ends bent or curved outwardly. Plates 73 are of a height as shown in Fig. 4, said plates and board 70 having their lower edges some distance above 20 the top surface of table 13. Brackets 71 have outwardly extending lugs 71a which are secured by headed and nutted bolts 74 to certain links of chains 75 disposed at each end of table 13. Chains 75 at their forward ends run over 25 sprockets 76, which sprockets are secured to a shaft 77 journaled in lugs 10g of end members 10 and in brackets 78 secured to the bottom of table 13. Shaft 77 has hand wheels 79 secured thereto at each end, the same having outwardly 30 projecting handles 79a thereon shown as four in number. The chains 75 at their rear ends run over sprockets 80 journaled on shafts 81 and held thereon by washers 82 and cotter pins 83. Each shaft 81 has an enlarged portion or block 81a of 35 square or rectangular form, substantially fitting in and slidable in a bracket 84 secured to the bottom of table 13 by the bolts 85. A set screw 86 extends into the forward end of bracket 84 and engages portion 81a, said set screw being shown 40 as provided with a jam nut 87. It will be seen that by turning screw 86 shaft 81 can be moved rearwardly to tighten chain 75. Brackets 71 have slots at their lower ends into which fit the outer edges of the plates 19, said brackets being 45 slidable on plates 19. A bracket 88 is secured to each rear outer corner of table 13, the same being secured by bolts 89. Each bracket 88 is apertured at its upper end to receive a pin 90 which projects through said bracket and through the 50 end of a socket bracket 91 similar to bracket 65 already described, which is disposed at the left hand end of bar 67 as seen in Fig. 2. A bar 92, square in cross section, fits into the end of bracket 91 and extends from said bracket to another socket bracket 93 into which its other 55 end is fitted. Bracket 93 is similar to bracket 65 shown in Fig. 2 and has a pin 94 extending through its end on which it is journaled, said pin also extending through the upper end of a bracket 95 secured to the upper rear side of end members 10 by the bolts 96. It will be understood that there is a bracket 95 and a bar 92 at each 60 end of the machine. A compression coil spring 97 surrounds pin 94 and is disposed in bracket 93, the same bearing at one end against the inner 65 end of bracket 93 and at its other end against the end of bar 92. Bar 92 has a plurality of marks 92a thereon with which a small plate bracket 98 carried by board 70 is adapted to align 70 to indicate the different positions of board 70 and thus the different positions for the rows of tufts in the mattress. Bar 92 has differently spaced marks on the various sides thereof and said bar may be turned to bring any side toward bracket 75 98.

In operation, the mattress 100 to be tufted is placed on the table 13. Board 70 at this time will be at the rearward limit of its movement. Board 70 can be moved forwardly and rearwardly by the operator turning one or the other of hand wheels 79. Rotation of these wheels turns sprockets 76, thus moving the chains 75 and the brackets 71. The rear side of the mattress is engaged by board 70 and the operator then rotates one of the wheels 79 to move the mattress forwardly, said mattress sliding on table 13. The mattress is moved until the location for the first row of tufts as desired is beneath needle 49 or in alignment with the bars 21 and 26. This position can be easily located by turning the wheel 79 until the thin bracket or pointer 98 registers with the first mark on the bar 92. Said bar 92 will have previously been turned to bring the side having the desired spacing of marks 92a toward bracket 98. With the mattress so positioned the operator 20 grasps one of the handles 32a and swings the same forwardly, rotating lever 32 forwardly. When the bars 21 and 26 are in separated position, the arm of lever 32 which is shown as extending downwardly in Fig. 4 will extend upwardly. The operator continues to swing lever 32 until it reaches the position shown in Fig. 4 and he usually engages both handles 32a in this operation. Bars 21 and 26 are moved toward each other to the positions shown in Figs. 1 and 4. 30 The mattress is now compressed between the convex surfaces of bars 21 and 26. The bars 21 and 26 are so arranged relatively to table 13, that each bar after engaging the mattress travels the same distance as the other bar so that the mattress is equally compressed from its top and bottom and when so compressed is compressed symmetrically about a horizontal plane. This is important, for if the mattress is compressed more from one side than the other and the tuft inserted, when the mattress is released the tuft will be a different distance from the top edge or corner of the mattress than it will be from the lower edge or corner. It is to get this equal compression that the pivots 31 and 37 are spaced different 40 distances from shaft 25. As lever 32 is swung, arms 38 are swung and counterweight 39 elevated. The lever 32 moves slightly past the dead center position relative to pivots 31 and 37 and shaft 25 so that said lever and the bars 21 and 26 45 remain in their positions adjacent each other with the mattress compressed. With the mattress so compressed the operator now grasps the handle of lever 52 and moves the carriage 47 lengthwise of bar 43. Spindle 48 is successively 50 alined with the marks on bar 67 and when so alined with a mark the operator pulls down on the end of lever 52, forcing the needle 49 through the mattress and to carry a tuft through said mattress in a manner well known in the art and as shown in the copending application of Walter H. Morley, for "Mattress tufting machine", filed November 2, 1932, Serial No. 640,829. It will be noted that the bar 43 and the carriage 47 move 55 downwardly with the bar 26 so that an excessive stroke or movement of spindle 48 is unnecessary. When spindle 48 is moved downwardly to pass needle 49 through the compressed portion of the mattress, springs 61 are extended and these springs act to return spindle 48 and needle 49 to their upper positions. The needle passes through the holes 21b and 21c as well as through the holes 26b, these holes being arranged to accommodate the desired spacings of the tufts. After 60 the row of tufts is completed across the mattress, 65 70 75

the operator again rotates lever 32, moving the bars 21 and 26 apart. He then again rotates one of the wheels 79, moving board 70 forwardly to bring member 98 into alignment with the next mark 92a after which lever 32 is again operated to move bars 21 and 26 and compress the mattress along a new zone. The mattress is compressed each time along a narrow zone extending thereacross. It will also be seen that table 10 22 is hinged to bar 21 and the inner end of said table can move upwardly with said bar, this movement being permitted by the pivotal connections at pins 22c and shaft 25.

From the above description it is seen that applicant has provided a simple, much improved and easily operated machine for tufting mattresses. By having the bars 21 and 26 convex at their adjacent surfaces the material of the compressed mattress is held only along a very narrow zone. There is also less tendency to tear the goods than where a flat surface is used and sharp corners are present. By having the carriage mounted on the upper compressor bar a smaller travel of spindle 48 is necessary to make the tufts. The arrangement of the bars 21 and 26 to have equal movement after engaging the mattress is also of great importance. As above stated, where the mattress is compressed more from one side than the other, the tufts are not spaced the same on one side of the mattress as on the other side. The present construction also requires very few guide members for the carriage and yet the same is very accurately held and guided in its movement. Means are provided for spacing the rows 30 of tufts as well as for spacing the individual tufts. The machine is constructed throughout so that a very rapid tufting can be performed. By having the bars 21 and 26 of concave form on their adjacent surface the mattress also slides over the same 35 with great ease. The machine has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth in the parts and combinations of parts 45 50 closed and defined in the appended claims.

What is claimed is:—

1. A mattress tufting machine having in combination, a support for a mattress, means for compressing said mattress along a narrow zone extending thereacross, means connected to and movable with said means and also movable longitudinally of said means for inserting tufts in said compressed zone at spaced points.

2. A mattress tufting machine having in combination, means for supporting a mattress, a pair of bars extending completely across said mattress above and below the same, means for moving said bars toward and from each other to compress said mattress therebetween along a narrow zone so as to be in condition to receive tufts, said bars having their adjacent surfaces convexly curved in transverse cross section at their adjacent sides and being provided with holes through which a tufting needle may pass.

3. A mattress tufting machine having in combination, means for supporting a mattress, members extending transversely of said means above and below said mattress and movable toward each other to compress said mattress along a narrow zone, means mounted on and movable with one

of said members and also movable longitudinally thereof to different positions for inserting tufts through said compressed zone.

4. A mattress tufting machine having in combination, a support for a mattress, members extending transversely of said mattress above and below the same and movable toward each other to compress said mattress along a narrow zone, a cross rail movable with one of said members in its movement toward the other member and a carriage movable longitudinally of said cross rail to different positions longitudinally of said members for inserting tufts in said mattress.

5. A mattress tufting machine having in combination, a support for a mattress, a narrow member extending transversely of said mattress above the same, a narrow member extending transversely of said mattress below the same, means for moving said members toward each other to compress said mattress along a narrow zone, a cross rail carried by said first mentioned member, a carriage movable longitudinally of said cross rail and said members, means movable vertically in said carriage carrying a needle for inserting tufts in said mattress through said compressed zone and means manipulatable by the operator for operating said last mentioned means.

6. A mattress tufting machine having in combination, means for supporting a mattress, a member extending transversely of said mattress above the same, means for moving said member toward said mattress to compress said mattress, a cross rail carried by said member, rollers running on said cross rail, a carriage supported by said rollers and cross rail, a vertically movable spindle in said carriage, a needle carried by said spindle and means movable by the operator for depressing said spindle and forcing said needle through said mattress to insert tufts therein.

7. The structure set forth in claim 6 and a bar carried by said cross rail having indications thereon with which said spindle may be aligned to space the tufts in said mattress.

8. A mattress tufting machine having in combination, means for supporting a mattress, a cross rail extending transversely of said mattress above the same comprising a narrow bar having beveled upper and lower sides, rollers having grooved peripheries fitting and engaging said sides, there being a plurality of rollers at one side of said bar, a carriage supported by said rollers and cross rail and movable longitudinally of said rail on said rollers and means mounted on said carriage for piercing a mattress to insert tufts therewith.

9. A mattress tufting machine having in combination, a cross rail, a carriage mounted for movement on said cross rail, rollers on said carriage engaging said rail and means for moving said rollers toward and from said rail to maintain a proper fit therewith.

10. A mattress tufting machine having in combination, a cross rail, a carriage mounted for movement on said cross rail, a stud in said carriage having an eccentric portion, a roller carried on said eccentric portion and engaging said rail, said stud being rotatable to move said roller toward or from said rail and means for holding said stud in fixed position.

11. A mattress tufting machine having in combination, a cross rail, a carriage mounted for movement on said rail, a stud secured in said carriage and having an eccentric portion, a ball bearing casing mounted on said eccentric portion, a roller mounted on said casing and engag-

ing said rail, means for holding said casing in said roller and means for holding said stud in fixed position whereby said stud may be rotated to move said roller toward or from said rail.

5 12. A mattress tufting machine having in combination, a support for a mattress, members disposed above and below said mattress respectively and in vertical alinement, means for moving said members together to compress said mattress along a narrow zone extending thereacross, a second member carried by said member above the mattress and movable longitudinally thereof and manually operable means movable vertically relatively to said second member for piercing said mattress in said zone and inserting tufts therein at desired spaced points.

10 13. A mattress tufting machine having in combination, means for supporting a mattress, members extending across said means above and below the same, links connected to said members respectively adjacent their ends, a lever journaled about a fixed axis and connected to said links respectively, said links being connected to said lever at opposite sides of said axis and at different dis-

tances therefrom, the link connected to said member above said means being connected the greater distance from said axis, whereby said links and members will be moved different distances by oscillation of said lever and said member above said means will be moved upward a greater distance than said member below said means will be moved downward.

15 14. A mattress tufting machine having in combination, means for supporting a mattress, members extending across said means above and below the same, links connected to said members respectively adjacent their ends, a lever journaled about a fixed axis and connected to said links respectively, said links being connected at opposite sides of said axis and at different distances therefrom, whereby said links and members will be moved different distances by oscillation of said lever, said lever having handle-equipped arms thereon extending substantially at right angles 20 to each other, an arm swinging with said lever and a counterweight carried by said last mentioned arm.

MARTIN H. LANG.
